CLAIM

The ornamental design for a cover for an electric fan, as shown and described.

DESCRIPTION

FIG. 1 is a top, front, and right side perspective view of a cover for an electric fan showing my new design; FIG. 2 is a front elevational view thereof; FIG. 3 is a rear elevational view thereof; and, FIG. 4 is a left side elevational view thereof, the right side being a mirror image of that shown.

FIG. 1

FIG. 2

FIG. 3

FIG. 4
